CLAIM

The ornamental design for a combined circular knife and guard, as shown and described.

DESCRIPTION

FIG. 1 is a perspective view taken from the knife side, showing the guard in the raised position;

FIG. 2 is a perspective view taken from the knife side, showing the guard in the lowered position;

FIG. 3 is a perspective view taken from the mount side, showing the guard in the raised position;

FIG. 4 is a perspective view taken from the mount side, showing the guard in the lowered and locked position;

FIG. 5 is an elevational view of the knife side, showing the guard in the lowered position;

FIG. 6 is an elevational view of the mount side, showing the guard in the lowered position;

FIG. 7 is a rear elevational view thereof; and,

FIG. 8 is a bottom plan view thereof.
